UNITED STATES PATENT OFFICE

2,593,870

ADJUSTABLE SIGHT RADIUS DEVICE FOR
FIREARMS

Henry F. Ganzhorn, Washington, Ill.

Application June 9, 1950, Serial No. 167,080

1 Claim. (Cl. 33—53)

1

This invention relates to gun sights, and more particularly to a device for selectively varying the sight radius of a gun.

An object of this invention is to provide a sighting device for attachment to a gun which permits the user to select any one of a plurality of sight radii.

Another object of this invention is to provide a sighting device for a gun which may be moved into and out of an extended position with respect to the forward end of a gun barrel for obtaining various sight radii of a length greater than the length of the gun barrel.

A further object of this invention is to provide a sighting device for attachment to a gun which is simple in structure and relatively cheap to manufacture.

The above and still further objects and advantages of this invention will become apparent upon consideration of the following detailed description of the invention when taken in conjunction with the accompanying drawings, wherein:

Figure 1 is a side elevational view of the adjustable sight radius device of the present invention shown supported on the forward end of a gun barrel;

Figure 2 is a top plan view of the adjustable sight radius device shown in Figure 1;

Figure 3 is a sectional view taken along the line 3—3 of Figure 1;

Figure 4 is a side elevational view of a modified form of the adjustable sight radius device of the present invention, shown supported on the forward end of a gun barrel; and

Figure 5 is a sectional view taken along the line 5—5 of Figure 4.

Referring now more particularly to the drawings, wherein like reference numerals have been used throughout the several views to designate like parts, there is shown the adjustable sight radius device of the present invention, generally designated by the reference numeral 10, supported on a gun barrel 11 contiguous to the fixed front sight 12 and spaced from the rear sight 13.

The adjustable sight radius device 10 includes an elongated base 15 which rests upon the forward end of the gun barrel 11 and is fixedly secured longitudinally thereof. As clearly shown in Figure 3, the base 15 is cut away to form a channelway 16 having a longitudinally extending flared tongue 17 rising from the bottom thereof.

Positioned upon the base 15 and mounted on the latter for sliding movement longitudinally

2

thereof into and out of an extended position with respect to the forward end of the gun barrel 11 is a slide 18. The slide is provided with a longitudinally extending slot 19 which is complementary to the flared tongue 17 and cooperates with the latter to form a dovetail joint for supporting the slide 18 for the sliding movement longitudinally of the base 15.

The extended end of the slide 18 is provided with a transversely extending slot 20 which slidably receives and supports a sight 21 of the globe or blade type, the base 22 of the sight 21 being dovetailed and complementary to the transversely extending slot 20. Accordingly, the sight 21 may be readily assembled or disassembled with the slide 18.

At spaced intervals along the upper exposed face of the slide 18 there is provided a plurality of transversely extending lines, generally designated by the reference numeral 23, each of the lines being provided with numerical indicia for indicating the position of the slide 18 with respect to the base 15, the base being provided with a reference line indicated by the numeral 24. As clearly shown in Figure 1, a side of the slide 18 is provided with a plurality of detent recesses, generally indicated by the reference numeral 25, the detent recesses being spaced along the length of the slide in substantial alignment with the transversely extending lines 23.

Extending transversely through the base 15 and selectively engageable in the detent recesses 25 is a detent 26 which is illustrated as a set screw including a threaded shank 27. Accordingly, the slide 18 can be secured at selected positions in its path of sliding movement corresponding to any one of the transversely extending lines 23.

The slide 18 is further provided with a longitudinally extending slot 28 which extends from a point adjacent to and spaced inwardly from the transversely extending slot 20 toward a point adjacent to and spaced inwardly from the other end of the slide 18. As clearly shown in Figures 1 and 2, the slot 28 accommodates the upper end of the fixed front sight 12, so that the slide 18 can be moved longitudinally of the barrel without the fixed sight 12 interfering with the sliding movement. Accordingly, the adjustable sight radius device 10 can be successfully utilized with either a gun including a fixed gun sight or one which does not have the conventional gun sight.

In actual use, the distance between the rear sight 13 and the adjustable front sight 21 may be selectively varied by moving the slide 18 to

any one of its extended positions with respect to the forward end of the gun barrel 11. It is to be noted that a sighting radius of a length somewhat greater than the length of the barrel 11 may be obtained by this arrangement. In the event that it is desired to obtain a sighting radius somewhat shorter than the length of the gun barrel 11, it is merely necessary to withdraw the slide 18 from the channel 16 and reinsert the slide into the channelway with the sight 21 overlying the gun barrel 11. From the foregoing, it is readily apparent that a wide range of sighting radii may be obtained with speed and facility.

In Figures 4 and 5, there is shown a modified form of the sighting device of the present invention, in which the base 15 is detachably secured to the gun barrel 11 by means of a clamp 30 which is either fixedly secured to the base 15 or formed integrally therewith. The clamp includes two arcuate arms 31, 32 complementary to the gun barrel 11, and having their free ends arranged in spaced confronting relation with respect to each other, as indicated by the reference numeral 33. Extending transversely through the free ends of the arcuate arms 31, 32 and threadedly engaging the latter is a set screw 34 for selectively urging the arms 31, 32 of the clamp 30 into embracing engagement with the gun barrel 11, to thereby detachably secure the adjustable sight radius device 10 to the gun barrel 11. From the foregoing, it is apparent that the adjustable sight radius device of the present invention can be utilized with any one of a plurality of rifles having different sizes of bores, as well as any number of shotguns and other firearms.

Numerous other modifications of the sighting device of the present invention can be made without departing from the spirit of the invention as set forth in the appended claim.

What I claim is:

The combination with a gun barrel having a

front sight rising therefrom and a rear sight rising from the barrel rearwardly of the front sight, of a base mounted on the barrel between the front and rear sights, said base having a longitudinal slideway in its upper side, a slide confined in said slideway and adjustable therein longitudinally of the gun barrel, said slide having a forward portion extending forwardly from said base and formed with a longitudinal slot receiving the front gun barrel sight, another front sight on the forward end of the slide and located forwardly of the front sight of the gun barrel, detent means acting between said base and said slide for securing said slide in selected longitudinal adjustment relative to said base and the gun barrel, said forward portion of the slide being formed with a transverse slot in its upper side, and said other front sight having a portion slidably confined in said slot whereby said other front sight is transversely adjustable across said slide.
